(57) **CLAIM**

The ornamental design for an electronic device holder, as shown and described.

DESCRIPTION

FIG. 1 is a perspective view of an electronic device holder showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines illustrate portions of the electronic device holder that form no part of the claimed design. The partially visible broken line in FIG. 1 illustrates a continuous inner edge of a central opening, wherein the broken line and the interior space beyond the broken line form no part of the claimed design.
